UNITED STATES PATENT OFFICE

153,116

DESIGN FOR A REMOTE CONTROL SELECTOR CABINET FOR PHONOGRAHS

Joseph J. Clement, Williamsville, and Harry C. Kline, Jr., Buffalo, N. Y., assignors to The Rudolph Wurlitzer Company, Chicago, Ill., a corporation

Application September 8, 1947, Serial No. 141,270

Term of patent 7 years

(Cl. D26—14)

To all whom it may concern:

Be it known that we, Joseph J. Clement and Harry C. Kline, Jr., citizens of the United States, residing at Williamsville and Buffalo, respectively, in the county of Erie and State of New York, have invented a new, original, and ornamental Design for a Remote Control Selector Cabinet for Phonographs, of which the following is a specification, reference being had to the accompanying drawing, forming part thereof.

In the drawings, Fig. 1 is a perspective view of a remote control selector cabinet for phonographs showing our new design. Fig. 2 is an end elevational view thereof.

The rear and underneath portions of the cabinet are plain.

We claim:

The ornamental design for a remote control selector cabinet for phonographs, as shown and described.

JOSEPH J. CLEMENT.
HARRY C. KLINE, JR.
